Patented Oct. 17, 1967

208,914

TOOL FOR MAGNETIZING AND DE-MAGNETIZING

Cloyd D. Smith, 13805 Rancheros Drive,
Reno, Nev. 89502

Filed Feb. 1, 1967, Ser. No. 5,651

Term of patent 14 years

(Cl. D26—1)

FIG. 1

FIG. 2

FIG. 3

FIG. 4

FIG. 5

FIGURE 1 is a top plan view of a tool for magnetizing and de-magnetizing, showing my new design;

FIGURE 2 is a side elevational view, the opposite side being substantially similar in appearance;

FIGURE 3 is a bottom plan view;

FIGURE 4 is an elevational view of the left-hand end of FIGURE 2; and

FIGURE 5 is an elevational view of the right-hand end of FIGURE 2.

I claim:

The ornamental design for a tool for magnetizing and de-magnetizing, as shown and described.
